(57) **CLAIM**

The ornamental design for a cash register drawer as shown and described.

DESCRIPTION

FIG. 1 is a perspective view of a cash register drawer, showing my new design;

FIG. 2 is another perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof;

FIG. 8 is a bottom plan view thereof;

FIG. 9 is a perspective view thereof when it is closed; and, FIG. 10 is an enlarged view of the encircled region 10 in FIG.1.

The dash-dash lines in the drawings illustrate portions of the cash register drawer that form no part of the claimed design. The dot-dash broken lines in FIGS. 1 and 10 depict the boundaries of the enlargements and form no part of the claimed design.
